Attorney

UNITED STATES PATENT OFFICE

PAUL V. TROUPE, OF KADOKA, SOUTH DAKOTA

SHOVELING OR SCOOP BOARD FOR FARM WAGON BOXES

Application filed December 6, 1930. Serial No. 500,474.

This invention relates to improvements in shoveling or scoop boards for farm wagon boxes.

The main object of the invention is to provide a scoop or shoveling board so constructed that it may be readily applied to the wagon to serve in an efficient manner both as a shoveling board and end gate for the wagon.

Another object is to provide a scoop or shoveling board of the above character in a simple, durable and relatively cheap form.

With these and other objects in view the invention resides in the novel construction and arrangement of parts as hereinafter set forth and claimed, reference being had to the accompanying drawings wherein:

Figure 1 is a plan view, partially broken away, showing the shoveling board attached to the wagon box and in its opened position.

Figure 2 is a vertical section through the structure shown in Figure 1, the shoveling board also being shown in dotted lines in its closed position.

Referring now more particularly to the drawings the reference character A designates the wagon box and B my improved shoveling board. In conventional manner the box A has the sides 1 and bottom 2 and the cleats 3 vertically set within the said sides at their rear ends as shown.

My invention comprises a hinge butt or attaching plate 4 of a length equal to the inner width of the wagon box A and secured in any suitable manner as shown by the flat head countersunk screws 4a on the bottom 2 thereof at its rear edge. The plate 4 has spaced hinge loops 5 formed along its rear edge and side plates 6 extended upward from its ends, the said side plates being offset and formed U-shaped in cross section as shown at 7 to fit around the cleats 3 to which they are secured by bolts 8 in the manner shown. These side plates 6 may be formed integrally with the plate 1 or provided separately and secured thereto as desired. The shoveling board proper comprises a rectangular back plate 9 provided at its lower or forward end with spaced hinge loops 10 adapted to mesh with or fit between the aforesaid hinge loops 5 on the hinge butt or attaching plate 4. This

plate 9 is then hinged to the plate 4 by a hinge rod 11 passing through the hinge loops 5 and 10. This hinge rod 11 is removable for a purpose to be described and to facilitate this removal it is provided on one end with a ring 55 or eye 12. Wings 13 are extended at right angles from the sides of the plate 9 and may be formed integrally therewith or, as shown in the drawings, may be secured thereto by bolts 14 passed through the flanges 15 provided on the said wings. The back plate 9 is of such width that the wings will pass within the side plates 6 as the plate 9 is swung upward to its closed position indicated in the dotted lines in Figure 2, the said wings 65 closely fitting the said side plates thus effectively preventing the escape of grain from the wagon box.

The upper bolts 8 holding the side plates 6 to the cleats 3 are provided on their outer ends with eyes 16 and 16a and a chain 17 is attached at one end to the eye 16 as shown by means of a conventional snap hook 18 or similar fastening device. Loops or eyes 19 are secured to the under or rear side of the back plate 9 near the sides thereof and at some distance outward from its hinged connection to the attaching plate 4. The chain 17 is passed rearwardly from its connection to the eyes 16 and is then passed laterally 80 across the plate 9 through the loops or eyes 19 and forwardly where it is connected at its other end by a snap hook or similar fastener 20 to the eye 16a. This chain thus serves to support the shoveling board in its lowered position and when the board is swung up to its closed position the chain is pulled taut through the eye 16a and the hook 20 is engaged with one of the links to hold the shoveling board closed in which position it serves 85 also as an end gate.

The operation and utility of my invention will be understood from the foregoing. When it is desired to simply dump grain or the like from the wagon box the hinge rod 11 is removed and the lower end of the shoveling board is swung outward. The shoveling board may of course be entirely removed by removing the hinge rod and unhooking 95 the chain 17. The device is so constructed 100

that it may be readily formed entirely of metal increasing its efficiency and wearing qualities.

While I have herein set forth a certain preferred embodiment of my invention it is understood that I may vary from the same in minor structural details, not departing from the spirit of the invention and within the scope of the appended claim.

10 I claim:

In a device of the kind described, in combination with a wagon box including a bottom and sides and cleats set vertically within the sides, an attaching plate secured to the bottom at the end thereof, hinge loops on the attaching plate, side plates formed integrally with the attaching plate and extended upwardly from the ends thereof around the said cleats on the wagon box, bolts passed outwardly through the side plates and cleats adjacent the upper ends thereof, eyes on the outer ends of the said bolts, a back plate, hinge loops along one edge of the back plate, a hinge pin removably passed through the hinge loops on the attaching plate and back plate, wings secured to the sides of the back plate, loops secured to the back plate near its sides and remote from the edge bearing the hinge loops, a chain passed loosely through the said loops, and snaps on the ends of the chain for engagement with the said eyes on the bolts.

In testimony whereof I affix my signature.

PAUL V. TROUPE.
